UNITED STATES PATENT OFFICE.

BURT R. VAN VALKENBURG, OF OAKLAND, CALIFORNIA.

WEB-GUIDING DEVICE.

1,259,321.

Specification of Letters Patent.

Patented Mar. 12, 1918.

Application filed February 28, 1916. Serial No. 80,860.

To all whom it may concern:

Be it known that I, BURT R. VAN VALKENBURG, a citizen of the United States, residing at Oakland, in the county of Alameda and State of California, have invented certain new and useful Improvements in Web-Guiding Devices, of which the following is a specification.

This invention relates to improvements in web controlling devices and has for its object the construction of a mechanism by which a web is held central in a given track.

Another object is to provide a device which may be used with a web, either wider or narrower than the normal width of web.

Still another object is to provide a controlling device which will not operate due to torn places in the edge of the web.

The invention consists in certain novel features and arrangements of parts by which the above objects are attained and which are fully set forth in the following specification.

Referring to the drawings forming a part of this specification,

Figure 1 is a view in plan showing the manner of applying my improved controlling mechanism to a tracker for automatic player pianos.

Fig. 2 is an enlarged view in plan of the double bellows by which movement of the web holding members is effected.

Fig. 3 is a view in section on 3—3, Fig. 2.

Fig. 4 is a view in section on 4—4, Fig. 2.

Fig. 5 is an enlarged sectional view through one of the members which contacts with the edges of the web.

Fig. 6 is a view in section showing one of the web holding bearings.

Fig. 7 is a view in section showing the means for adjusting the driving shaft and shifting means.

Fig. 8 is a detail view showing the means for adjusting the contact members.

Referring to corresponding parts in the several views by the same numerals of reference, 1 denotes a web which passes over the bar 2, this web being wound from the spool 3 to the spool 4. A shaft 5 is driven from a suitable motor, which it is not deemed necessary to here illustrate, and mounted

thereon is a gear 6 adapted to mesh with gear 7 upon the shaft 8, thereby driving the spool 4. The gear 6 is splined on shaft 5, and has formed on its side a grooved member having clutch teeth 9, adapted to engage corresponding teeth in a sprocket gear

10, which in turn is connected by a chain 10' to a similar gear 11 on shaft 12, this shaft driving the spool 3. An operating handle is denoted by 13, which engages the clutch member and shifts the same along shaft 5 so as to engage either the gear 7 or the sprocket 10, thereby causing the web to be wound either upon the spool 3 or 4.

Mounted on the side walls 14 are two valve members, denoted in general by 13, comprising the body portion 16, in which is slidably mounted a rod 17 provided with an enlarged head 18 adapted to contact with the edge of the web. This head is held extended by means of a light spring 19 seated in a recess 20 in the inner end of the body 16 and abutting against the underside head. The opposite end of the body member is provided with a passageway 20' normally closed by means of the disk 21, attached to the outer end of rod 17 and provided with a washer 21 of soft flexible material. This closure is held seated by means of spring 19, as well as by the vacuum in passageway 20'. 80

The end of member 16 is provided with a cap 22 of fine mesh material fabric, which entirely surrounds the closure, thereby preventing the entrance of dust and fine particles into the passageway 20' when the valve is lifted therefrom. One of these members is provided in each side of the frame 14, the heads 18 thereof contacting with the edges of the web and the openings 20' of each of these members being normally closed. 90

To permit adjustment of members 15 for different widths of web, I provide the body portion 16 with pins 83, which are engaged by a shipper yoke 82. The latter is attached to a rod 81 oscillatably mounted in a bearing plate 80 secured to the side of frame 14. To the bottom of one of the rods 81 is secured an operating lever 84, and to the opposite rod 81 is secured a short lever 86, which is cross-connected to the operating lever 84 by a link 85. The connection of the levers is such that the members 15 are equally moved away or toward the center of the web. 100

I will now describe the bellows by which the position of the spool 3 is controlled.

This bellows consists of the stationary portion 24 of substantially double wedge shape having the wider portion symmetrically disposed between the ends thereof. Attached to this member by means of a flexible strip 25, is a similar shaped block 26 and

around the outer edges of these blocks is a membrane 27 forming in effect a double bellows. Block 24 is rigidly secured to some fixed part of the machine frame leaving 26 free to oscillate on the strip 25.

5 Mounted on the upper surface of member 24 is a strip 28 and interposed between this member and 24 is a layer of fabric such as leather, denoted by 30. The latter is provided with a cut out portion 31, thereby forming a shallow cavity, 32, connected by a passageway 33 with a suitable source of producing vacuum. Formed in the upper surface of the block 24 are cells 34 and 35, over 10 which are diaphragms 36 separating the cell from the cavity 32. Adjacent these cells are recesses 37 and 38 respectively, these recesses being provided with a gauze covering 39, communicating with their adjacent cells 15 by means of passageways 40.

20 In the plate 28 is provided passageways 41 and 42, extending from the outer surface of the plate to a point above the cells 34 and 35. These passageways having branches 43 25 and 44 communicating with the recesses 37 and 38, and bleedholes 49 communicating with the cavity 32.

25 In alignment with the axis of each of the cells 34 and 35 are vertical passageways 50 extending upwardly to the surface of plate 28 and extending laterally therefrom are passageways 51 and 52 communicating with other passageways 53 and 54 to the interior of each of the bellows.

30 Mounted on the outer surface of plate 28 are flexible strips 55 of material such as leather, which strips are adapted to cover the opening of passageways 50, and fast to the interior surface thereof are pins 56 extending downwardly through this passageway and resting on the pad 57 on the upper surface of the diaphragms 36.

35 The underside of the movable member 26 is provided with a block 60 wherein is mounted a pin 61. Revolvably mounted in the frame member is a shaft 63, having a lever 62 on one end, which is slotted to engage the pin 61. To the other end of this shaft is attached a lever 64 connected by a 40 link 65 to a pin 66, which pin engages the shaft 12 extending through an inclined slot 67 in the sleeve 68. The valve members 15 are connected by tubes 70 and 71 with the passageways 41 and 42 respectively.

45 55 One end of the spool 3 is seated in a holding device on shaft 12, while the other end is seated in the holding device 73, which is provided with a spring 74 to urge the holding member 73 outwardly and allow the 60 spool to be inserted and removed in the holding means.

The operation is as follows:

55 If for any cause the upper spool or the web thereon should move, say, to the right, 65 then the edge of the web on this side con-

tacts with the head 18 of the valve member 15 on that side, opening the passageway 20' therein, admitting atmospheric pressure to the tube 71 leading to the double bellows 23. The air flows through the passageway 70 42 to cavity 38, through the passageway 40 to cell 35; the diaphragm 36 on the opposite side of which a vacuum is used is thereby raised upwardly causing the pin 56 to lift the flexible strip 55, which in turn admits atmospheric pressure through the passageways 50, 52 and 54 to the end of the bellows marked A. The air having been exhausted from the opposite end B of the bellows, this end then collapses, which causes 80 the end A to expand, raising the pin 61 and correspondingly rotating the shaft 63. The rotation of this shaft, through the levers 64 and pins 66 and the connecting link 65, rotates the block 68 in such a direction that 85 the shaft 12 is moved to the left and is held in this position as long as the edge of the web laps over its normal position. When the edge of the web assumes its normal position the washer 21 under the action of 90 spring 19 closes the passageway 20' and allows the bellows and other parts to assume their normal central position.

95 In case the web is tracking properly but the entire width is greater than normal, then by the movement of lever 84 the distance between the opposite devices 15 may be increased to accommodate the increased width of the web. The web may be adjusted centrally on the tracker bar by turning the screw 72 in the block 68, which shifts the shaft relative to the block 68 and the tracker bar, but does not change the position of the block, any difference in the position of the shaft being taken up by the 105 spring in the opposite holding device.

100 What I claim as new and wish to cover by Letters Patent is:—

110 1. A web guiding device comprising a roll, a web, a take up spool, valve members adapted to yieldably bear against the edges of said web, said member having ports opened by the pressure of the web against the yieldable portion, pneumatic means comprising a bellows including a pair of 115 wedge-shaped members, having their widest portions symmetrically disposed between the ends thereof, a hinge joining said members together at such widest portion and a membrane enveloping the outer edges of 120 said wedge-shaped members, and actuating mechanisms connected to one of said wedge-shaped members whereby when one of the same is oscillated, the mechanism is caused to shift the roll so as to bring said web into 125 its central position.

130 2. A web guiding device comprising in combination a roll, a web, a take up spool, valve members adapted to yieldably bear against the edges of said web, said mem-

- bers having ports opened by the pressure of the web against the yieldable portion, pneumatic means comprising a bellows including a pair of wedge-shaped members, having 5 their widest portions symmetrically disposed to the ends thereof, a hinge joining said members together at such widest portion, and dividing said bellows into two chambers, a membrane enveloping the outer 10 edges of said wedge-shaped members and passages connecting the valve ports to one or the other chamber formed in said bellows, whereby when said ports are opened, air is admitted to one of said chambers 15 causing one of said wedge-shaped members to oscillate with respect to the other and means connected to said oscillating part whereby to shift the roll and bring the web into its central position.
- 20 3. A web guiding device comprising in combination a roll, a web, a take up spool, members adapted to yieldably bear against the edges of said web, said members having ports opened by the pressure of the web 25 against the yieldable portion, pneumatic means comprising a bellows including a pair of wedge-shaped members having their widest portions symmetrically disposed to the ends thereof, a hinge joining said mem- bers together at such widest portion and di- 30 viding the bellows into two separate cham- bers, one of said wedge-shaped members being formed with passages communicating with the outer atmosphere, such passages, however, being normally closed by means 35 of valve members provided with a down- wardly extending stem, a diaphragm adapt- ed to bear against the free end of said valve stem whereby to unseat the said valve mem- ber, the wedge member being provided with 40 a secondary passage connected to a suitable source of vacuum which is adapted to act upon said diaphragm, a membrane envelop- 45 ing the outer edges of said wedge shaped members and tubes connecting the ports to the passages communicating with said dia- phragms whereby when said ports are opened, air is admitted to said passages 50 whereby the vacuum acting upon the dia- phragms is broken whereby one wedge- shaped member is caused to oscillate with respect to the other and means connected to said oscillating part whereby to shift the roll, and consequently the web into its sec- 55 ondary position.

In testimony whereof I affix my signature.

BURT R. VAN VALKENBURG.
